LOCKING DEVICE

George Phillips Mahood, Bluefield, W. Va., assignor to Bethlehem Steel Company, a corporation of Pennsylvania

Application November 19, 1936, Serial No. 111,565

11 Claims. (Cl. 238—338)

My invention relates to improvements in locking devices and more particularly to locking devices for rail fastening clips.

In some types of railway track construction, particularly those of the light character used in mines and construction work, it is desirable to have the rails readily attachable and detachable with respect to the ties, while at the same time it is desirable to have the rails firmly secured to the ties at all times when they are in use. To this end it has been the practice to employ ties having rotatable clips to engage one side of the rail and a fixed clip to engage the other side of the rail so that a rail may be readily attached to the ties by driving the rotatable clips into engagement with the rail, or detached from the ties by disengagement of the clips from the rail. These rotatable clips are generally fastened to the ties by rivets in such a manner so that when the ties are first installed with a rail the clips frictionally engage the tie and therefore they are not easily jarred loose due to traffic passing over the rail when the clips are in their assembled relation with the rail. However, after the ties have been used several times the rotatable clips become loose so that they rotate easily on the tie and are easily jarred loose from their assembled position with the rail due to traffic passing thereover. It is therefore the main object of my invention to obviate this condition by providing a locking device which engages the rotatable clips to retain them against rotation when they are in their assembled relation with the rail even though the clips are easily rotated.

Another object of my invention is to provide a locking device or key for locking the movable clips against rotation at all times when they are in their assembled condition with the rails.

A further object of my invention is to provide a locking device or key for locking the rail clips against displacement with means to retain the device in its assembled relation with the tie at all times so that it will not become misplaced or lost when the ties are detached from the track structure.

A still further object of my invention is to provide the locking device with means to retain the locking device in its locked relation with the clips when the clips are in their assembled relation with the rail.

The novel features of my invention will be more fully understood from the following description and claims taken with the drawings in which:

Fig. 1 is a top plan view of a portion of a track structure embodying my novel device;

Fig. 2 is a sectional view taken on line 2—2 of Fig. 1;

Fig. 3 is a plan view showing the rotatable clips in their initial engagement with the rail and my locking device in engagement with the clips;

Fig. 4 is a plan view showing my device in its final or locking position; and

Fig. 5 is a view in elevation illustrating a modified form of my invention.

Referring to the drawings, 10 designates a metallic tie for supporting a rail 11 and is provided with clips 12 and 13 for fastening the rail to the tie. The tie 10 is provided with a longitudinal groove 14 in its upper surface and the clip 12 is connected to the tie in bridging relation with the groove 14 by suitable fasteners 15. The clips 13 are mounted on opposite sides of the groove 14 and are pivotally connected to the tie 10 by means of suitable fasteners 17, so that they are rotatable into and out of engagement with the rail 11. Mounted in the groove 14 and extending beneath the clip 12 is one of my novel locking devices or keys 18. The device 18, as shown in Figs. 1 to 4, comprises an elongated body or under rail portion 19, which terminates at one end in an upwardly and inwardly bent hook portion 20 and at the other end in an upturned toe portion 21, which is substantially T-shaped in cross section and comprises the vertical web 22 and the flanges 23 and 24. Referring to Fig. 4 wherein I show the device 18 in its assembled relation with the track structure, after the rotatable clips 13 have been rotated into engagement with the rail 11 and the device 18 has been driven to its locked position, the toe portion 21 is in engagement with the clips 13 beyond their pivoted point provided by the fastening means 17 and effectively prevents the rotation of the clips towards the position shown in Fig. 3, and the hook portion 20 is in clamping engagement with the clip 12 and therefore the device 18 is effectively retained in its locking position. A recess 25 may be provided in the clip 12, as shown in Figs. 1 and 2, to receive the end of the hook portion 20 to assist in retaining the device 18 in its locking position where the track structure is to be subjected to excessive vibration, but the clamping action of the hook portion 20 with the clip 12 is sufficient in ordinary cases to retain the device in its locking position as shown in Fig. 4.

In Fig. 5 I show a modified locking device 29, which is preferably made of spring steel and is provided with a slightly arched body portion 30, a hook portion 31 and a toe portion 32. The hook portion 31 is similar to the hook portion 20

20 of the locking device 18 but the toe portion 32 is provided with a round outer portion 33. The arched portion 30 is so formed that its highest point is forced down beneath the fixed 5 clip 12 when the locking device is in the position similar to that shown in Fig. 1, so that it will not interfere with the installation of the rail 11 with the tie 10. After the rotatable clips 13 have been assembled with the rail and the locking device 29 has been forced into locking engagement with the clips, the body portion 30 of the device tends to resume its original bowed condition and effectively grips the under surface of the base of the rail and the bottom of 15 the groove and together with the hook portion 31 effectively retains the locking device in its assembled condition under the most severe conditions.

My novel locking devices 18 and 29 are assembled with the tie 10 by placing either the device 18 or 29 in the groove 14 of the tie 10 and then mounting the clip 12 thereon and fastening it to the tie by suitable means such as the fasteners 15. The hook portion and the toe 25 portion prevent the device from becoming separated from the tie after the clip 12 has been placed thereon and therefore after the locking device is assembled with the tie there is no danger of it becoming misplaced or lost even when 30 the tie is not in use and therefore the locking device is always ready for use when the tie is assembled with a rail.

In assembling the rail 11 with the tie 10, the rail is placed on the tie with one flange of the 35 rail base adjacent the fixed clip 12, the rotatable clips 13 and the locking device being in the position shown in Figs. 1 and 2. That is, with the flanges 23 and 24 engaging the clips 13, if the device 18 is used, and the web 22 passing between 40 the clips 13. The rotatable clips 13 are then rotated by any suitable means such as the blow from a track hammer onto the opposite flange of the rail base to the position shown in Fig. 4. This action of the rotatable clips forces the rail 45 base flange under the fixed clip 12, as shown in Figs. 3 and 4. The clips 13 may be initially rotated by means of the locking device to the position shown in Fig. 3 by striking the hook portion of the locking device with any suitable 50 means such as a track hammer. This will also tend to drive the clip 12 over the flange of the rail, whereas, if the rotatable clips are initially driven with a hammer the force transmitted to the tie will tend to drive the fixed clip 12 away 55 from the rail. After the rotatable clips have been rotated to their assembled position, the locking device 18 or 29, whichever is used, is then driven to the position shown in Fig. 4 by any 60 suitable means. This forces the toe portion of the locking device between the clips 13 so that the clips are prevented from rotating outwardly toward the position shown in Fig. 3. The driving of the locking device into engagement with the rotatable clips 13 at the same time causes 65 the hook portion of the locking device to be forced into clamping engagement with the fixed clip 12, and, if a recess or depression is provided in the clip 12, the end of the hook portion enters said recess.

70 From the foregoing it will be obvious to those skilled in the art that I have devised an improved locking device for the clips of a tie which is simple in construction, which permits easy assembly of the rail with the tie or the dismantling 75 thereof, and which provides a very efficient lock-

ing means for the clips when they are in assembled relation with the rail.

While I have shown my invention in a plurality of forms, it will be obvious to those skilled in the art that it is not so limited but is susceptible to various other changes and modifications without departing from the spirit thereof, and, I desire, therefore, that only such limitations shall be placed thereupon as are imposed by the prior art or as are specifically set forth in the appended claims.

Having thus described my invention what I claim as new and desire to secure by Letters Patent is:

1. A locking device, a clip rotatably mounted on a tie independently of the locking device and retained by said locking device in its assembled position with a rail of a track structure, said device comprising an elongated body portion, a toe portion integral with one end of the body portion adapted to engage the rotatable clip and a hook portion integral with the other end of the body portion adapted to engage a member of the track structure to retain said locking device in its assembled condition with the clip. 15

2. A locking device, a clip rotatably mounted on a tie independently of the locking device and retained by said locking device in its assembled position with the structure to which it is applied, said device comprising an elongated body portion, 30 adapted to extend beneath a member of said structure, a toe portion integral with one end of the body portion adapted to engage the rotatable clip and a hook portion integral with the other end of the body portion adapted to engage a member of the structure to retain said device in its assembled condition with the clip. 35

3. A locking device for retaining a pair of rotatable clips in assembled position with a structure to which they are applied, said device comprising an elongated body portion, adapted to extend beneath a member of said structure, a hook portion extending from one end of the body portion and a toe portion extending from the other end of the body portion adapted to engage and rotate the rotatable clips, said toe portion comprising a T-shaped portion having its web adapted to pass between the rotatable clips, and its flanges adapted to engage the rotatable clips to initially rotate said clips upon the movement 45 of the locking device towards its assembled position, and to retain said clips against rotation when the locking device is in its assembled position with the structure. 50

4. A locking device for clips which are rotatably mounted on a tie independently of the locking device, said locking device comprising a body portion, a hook portion integral with one end of said body portion and a toe portion integral with the other end of said body portion, said toe portion comprising a T-shaped portion the flanges of which are adapted to lockingly engage the rotatable clips. 55

5. A locking device for retaining a rotatable clip in its assembled position with a rail of a track structure, said device comprising an elongated body having a bowed portion, a toe portion integral with one end of the body adapted to engage the rotatable clip and a resilient hook portion integral with the other end of the body 65 adapted to engage a member of the track structure in clamping engagement therewith to retain said locking device in its assembled condition. 70

6. In combination with a metallic tie having a groove in the upper surface of the tie, rail 75

clamping means mounted on said tie, said means comprising a movable clip pivotally mounted on said tie on one side of said groove and locking means slidably mounted in the groove of said tie adapted to engage the clip to retain said clip against rotation.

7. In combination with a metallic tie having a groove therein, rail clamping means mounted on said tie, said means comprising a stationary 10 clip bridging said groove and a pair of rotatable clips in spaced relation to said stationary clip and mounted on opposite sides of said groove and a locking device slidably mounted in the groove beneath the stationary clip and adapted 15 to engage the rotatable clips to retain said clips against rotation.

8. A metallic tie having a groove in its upper surface, rail clamping means mounted on said tie, said means comprising a clip adapted to engage one side of a rail base flange and a pair of 20 rotatable clips adapted to engage the other side of the base flange of the rail, and a locking device slidably mounted in the groove of the tie for locking the rotatable clips in engagement with 25 the rail.

9. A metallic tie having a groove in its upper surface, rail clamping means mounted on said tie in bridging relation to said groove and having a depression in its upper surface, a pair of 30 rotatable clips mounted on said tie in spaced relation to said clamping means, a fastening device

for said rotatable clips, said device comprising a body portion slidably mounted beneath said clamping device, a toe portion adapted to engage said rotatable clips and a hook portion adapted to be brought into clamping action with said clamping means and to enter said depression to retain the fastening device in its assembled position when the clamping device and the rotatable clips are in assembled relation with a rail placed on the aforementioned tie.

10. A metallic tie having a longitudinal groove in its upper surface, a fixed clip mounted on said tie in bridging relation to said groove, and adapted to engage one flange of a rail, a rotatable clip mounted on said tie to one side of the 15 groove adapted to engage the other flange of a rail, and a locking device for said rotatable clip 20 slidably mounted in said groove and slidably longitudinally of said groove and having means to cooperate with said fixed clip to retain the locking device in its assembled condition.

11. A locking device for clips rotatably mounted on a tie independently of said locking device, said device comprising a body portion, a hook portion integral with one end of the body portion and an upturned toe portion integral with the other end of the body portion adapted 25 to lockingly engage the rotatable clips and retain them in their assembled position.
